UNITED STATES PATENT OFFICE.

HENRY R. HINTZE, OF DETROIT, MICHIGAN.

KEY-RETAINER.

1,297,168.

Specification of Letters Patent. Patented Mar. 11, 1919.

Application filed August 9, 1918. Serial No. 249,137.

To all whom it may concern:

Be it known that I, HENRY R. HINTZE, a citizen of the United States, residing at Detroit, in the county of Wayne and State 5 of Michigan, have invented new and useful Improvements in Key-Retainers, of which the following is a specification.

This invention relates to key retaining devices, the object being to provide a simple and inexpensive device by means of which a key may be quickly and easily secured within the lock from the inner side of the door, thereby preventing the insertion of keys or other instruments from the outer side of the door to guard against the unauthorized opening of the latter.

The invention also aims to provide a device of this character which may be removably secured through the shank of a door 10 knob in a manner to prevent its accidental removal so as to be in a convenient position for use, at the same time not presenting a bulky or cumbersome appearance or in any 15 way interfering with the removal or insertion of the key when not in use.

To this end the invention comprises a device formed of a single strand of spring wire bent centrally of its ends to provide a spring eye, substantially parallel arms curved inwardly at their extremities to form an elongated normally closed loop adapted for insertion over the shank of the door knob and key engaging legs formed of a continuation of the parallel arms and adapted for 35 insertion in the eye of the key.

In the drawings:—

Figure 1 is a front elevation showing the manner of using the invention, the door knob being shown by dotted lines and the 40 key in transverse section; and

Fig. 2 is an elevation at right angles to Fig. 1.

Referring to the drawings in detail, wherein like characters of reference denote 45 corresponding parts, the numeral 10 indicates a fragmentary portion of a door, 11 the knob, 12 the shank of the knob and 13 the key, which is provided with the usual opening 14 in the shank.

50 The invention which is adapted for the

purpose of preventing the removal of the key by the insertion of a key or other instrument from the outer or opposite side of the door, is formed of a single strand of spring wire and comprises a spring eye 55 15, which is formed of bending the wire central of its ends. The wire is then formed into substantially parallel arms 16, the extremities 17 of which are curved inwardly to form a normally closed elongated loop 60 18 which is adapted to receive the shank 12 of the door knob when the arms 16 are sprung over the latter. The inwardly curved extremity 17 terminating in legs 19, which are adapted to be inserted in the opening 65 14 of the key 13. These legs are in contact engagement at their extremities 20 and are gradually spaced apart toward their opposite ends to provide a wedge shaped element for entrance into the opening in the 70 shank of the key. This provides an opposite engagement between the retainer and the key, the wedge form snugly fitting keys having various sized openings.

By forming the loop 18 in the manner 75 specified, the retainer may be sprung over the knob 11 upon the shank 12 and remain thereon as long as desired, permitting of its insertion and removal from the opening in the key shank when the occasion arises. 80 When not in use the device in no way interferes with the ordinary use of the key and owing to its positive engagement with the shank remaining at all times ready for use.

Having described the invention, what is 85 claimed is:—

A key retainer formed of a single strand of spring wire bent centrally of its ends to form a spring eye, substantially parallel arms curved inwardly at their extremities 90 to form an elongated normally closed loop for engagement over the shank of a door knob and key engaging legs, said legs being in contacting engagement at their extremities and gradually spaced apart to form a 95 wedge shaped element for entrance into the eye of a key.

In testimony whereof I affix my signature.

HENRY R. HINTZE.
